Primary Examiner — Janice Hallmark(74) *Attorney, Agent, or Firm* — McGarry Bair PC(57) **CLAIM**

The ornamental design for a ceiling fan, as shown and described.

DESCRIPTION

FIG. 1 is a top perspective view of a ceiling fan;
FIG. 2 is a bottom perspective view of the ceiling fan of FIG. 1;

FIG. 3 is a top view of the ceiling fan of FIG. 1;
FIG. 4 is a bottom view of the ceiling fan of FIG. 1; and,
FIG. 5 is a front side view of the ceiling fan of FIG. 1, with
rear, right, and left side views being identical thereto.
Portions of the ceiling fan shown in broken lines form no
part of the claimed design.

1 Claim, 5 Drawing Sheets(56)
